(57) CLAIM

The ornamental design for a wedge for a gaming machine island, as shown and described.

DESCRIPTION

This application incorporates by reference the following applications in its entirety: U.S. patent application Ser. No. 29/750,266, filed Sep. 11, 2020. All disclosure and subject matter, including all figures, of this application is specifically incorporated by reference in this application as if set forth fully herein.

FIG. 1 is a front perspective view of a wedge for a gaming machine island showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is another front perspective view thereof, showing the wedge for a gaming machine island separately for clarity of illustration;

FIG. 9 is another front elevation view thereof, showing the wedge for a gaming machine island separately for clarity of illustration;

FIG. 10 is another left side elevation view thereof, showing the wedge for a gaming machine island separately for clarity of illustration; and,

FIG. 11 is another top plan view thereof, showing the wedge for a gaming machine island separately for clarity of illustration.

The broken lines shown in FIGS. 1-7 illustrate environmental subject matter that forms no part of the claimed design. The broken lines in FIGS. 8-11 illustrate portions of the wedge for a gaming machine island that form no part of the claimed design.
